UNITED STATES PATENT OFFICE.

HARRY L. COMPTON, OF WASHINGTON, DISTRICT OF COLUMBIA.

ATTACHMENT FOR CLOSURE-DISK-MANUFACTURING MACHINES.

1,160,693.

Specification of Letters Patent.

Patented Nov. 16, 1915.

Original application filed March 12, 1913, Serial No. 753,866. Divided and this application filed July 22, 1914. Serial No. 852,430.

To all whom it may concern:

Be it known that I, HARRY L. COMPTON, a citizen of the United States, residing at Washington, District of Columbia, have invented certain new and useful Improvements in Attachments for Closure-Disk-Manufacturing Machines, of which the following is a specification.

This invention relates to certain improvements in attachments for closure disk manufacturing machines and the like, and the objects and nature of the invention will be readily understood by those skilled in the art in the light of the following explanation of the accompanying drawings illustrating what I now believe to be the preferred embodiments from among other formations, arrangements and constructions within the spirit and scope of this invention.

This case is filed as a division of U. S. Patent #1,113,932 for mechanism for packing disks and the like, filed March 12, 1913, Serial Number 753,866, and the particular object of this invention is to provide mechanism for preventing congestion of the closure disks in the passage between the discharge from the disk making machine and paraffining mechanism and for insuring delivery of said disks in the proper position to the paraffining mechanism.

The invention consists in certain novel features in construction and in combinations and arrangements as more fully and particularly set forth and specified hereinafter.

Referring to the accompanying drawings;—Figure 1, is a vertical sectional view through a portion of a disk making machine, paraffining mechanism and mechanism involving my invention for delivering the disks from said machine to said paraffining mechanism. Fig. 2, is a detail top plan view of the mechanism of my invention.

Fig. 3, is a detail side elevation thereof. Fig. 4, is a detail perspective somewhat diagrammatically illustrating certain parts.

In the drawings, I show an upright bed or frame 1, mounted on and rising from a pedestal 2. The bed 1, carries disk making mechanism involving generally the elements and arrangements approximately as disclosed by Patent No. 927,002 issued July 6, 1909, to American Dairy Supply Co. as the

assignee of F. L. Nichols for machine for 55 making cover or closing disks.

In this machine a ribbon of disk stock *a*, is fed with a step by step movement under the vertically movable punch 6, and over the annular die 9, and the punch and die co-operate in cutting the complete disks from the ribbon of disk stock. The die 9, is formed in or carried by the die block 10, and this die block is formed with a vertical discharge passage 11 (surrounded at its upper end by die 9) opening through the under side of the block. The punch 6 cuts out the disks and forces them down into said discharge passage, so that disks are dropping from the lower end of the passage 70 as the freshly cut disks are forced into the upper end of the passage.

If the completed disks are to be treated with material (paraffin for instance) to render them non-absorbent, I provide suitable mechanism for this purpose. For instance, in the particular example illustrated, I show an open top paraffin pot 12, provided with suitable means for supplying the necessary heat to keep the paraffin in 80 liquid condition. This pot is arranged in front of the pedestal and is usually secured thereto and supported thereby below the level of the discharge end of passage 11, and a distance in front thereof. In the pot I 85 show a horizontal transversely arranged rotary paraffining roll 13, having an absorbent material surface dipping into the liquid paraffin in the pot. This roll is carried and driven by a suitable shaft 14, carried 90 by the pot and extending to the exterior of the ends thereof. At one end this shaft is provided with pulley 15, to which power is applied for rotating roll 13, so that its upper surface will move forwardly.

An absorbent material-surface paraffining and pressure roll 16, is arranged above and co-operates with and is driven by roll 13. The pressure roll shaft is carried by adjustable boxes confined in brackets 17, fixed 100 to and rising from the pot ends. A stripper roll 18, is shown engaging the upwardly moving rear side of the paraffin roll 13, to remove surplus paraffin therefrom.

Means are provided for receiving the 105 completed disks discharged from the lower end of passage 11, and delivering the same one at a time onto the forwardly moving

upper surface of the paraffining roll 13, so that the disks will be carried forward between the paraffin saturated surfaces of rolls 13, 16, and will absorb the desired quantity of paraffin therefrom.

In the particular example illustrated, I show conveying means for this purpose comprising a downwardly and forwardly inclined chute or trough 19, having a flat floor and vertical longitudinal edge walls spaced apart a distance slightly greater than the diameter of the disks. This chute is carried by an elongated supporting frame 20, at its upper portion having suitable supporting brackets 21, secured to any support such as the bed 1, or the pedestal 2. The chute is also supported by the transverse rotary cross shaft 22, mounted in and passing through the lower end of frame 20, and mounted in and supported by the brackets 15 21.

The upper end of the frame 20 is formed with longitudinal slots, receiving the transverse shaft 23, which is adjustable longitudinally of the chute and is held in the desired adjustment by adjusting and stop screws 24. This shaft 23, carries idler roll 25, mounted to rotate on the shaft between the longitudinal sides of frame 20. This 25 30 rotating roll is located directly below the discharge passage 11, so that the disks falling from said passage will drop onto said roll and be thereby directed forwardly in the chute. The upper surface of this roll 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 having its upper end arranged beneath said discharge to receive said disks, a roll arranged transversely in said slideway immediately below said discharge to receive 5 the disks dropping therefrom, and an endless disk propelling conveyer arranged longitudinally in said slideway.

5. A disk making machine provided with a pair of horizontally disposed coöperating 10 rolls and a slideway to convey the disks to said rolls, said slideway provided with rotating rolls forming a portion of the floor thereof and an endless chain between said rolls and arranged longitudinally and approximately centrally of the slideway to 15 prevent congestion of the disks therein.

6. In combination, an inclined chute, transversely rotating rolls in the end portions of said chute, the roll at the upper end of said chute having circumferential 20 portions exposed to engage disks dropped into the upper end of the chute, and an endless disk propelling conveyer driven by said rolls and having its upper ply arranged longitudinally and movable downwardly in 25 said chute.

In testimony whereof I affix my signature in presence of two witnesses.

HARRY L. COMPTON.

Washington, D. C."

Correction in Letters Patent No. 1,160,693.

It is hereby certified that Letters Patent No. 1,160,693, granted November 16, 1915, upon the application of Harry L. Compton, of Washington, District of Columbia, for an improvement in "Attachments for Closure-Disk-Manufacturing Machines," were erroneously issued to the inventor, said Compton, whereas said Letters Patent should have been issued to *American Dairy Supply Company, of Augusta, Maine, a corporation of Maine*, as owner of the entire interest in said invention, as shown by the record of assignments in this office; and that the said Letters Patent should be read with this correction therein that the same may conform to the record of the case in the Patent Office.

Signed and sealed this 7th day of December, A. D., 1915.

[SEAL.]

Cl. 164—22.

R. F. WHITEHEAD,
Acting Commissioner of Patents.
